SULPHONATION PRODUCT

Roland Kapp, Newark, N. J., assignor to National
Oil Products Company, Harrison, N. J., a cor-
poration of New Jersey

No Drawing. Application October 23, 1937,
Serial No. 170,596

12 Claims. (Cl. 260—402)

The invention relates, in general, to new chemical compounds and, in particular, to sulphonation products of certain esters of naphthenic acids.

5 Notwithstanding the great number of emulsifying, dispersing and wetting agents known and available on the market, there is a constant need for new agents of this type having novel and improved properties. Many materials which could 10 be employed to great advantage in an emulsified form cannot be emulsified satisfactorily due to the inadequacy of the emulsifiers heretofore known. Such materials include *inter alia* the polyvalent metal soaps of naphthenic acids such, 15 for example, as lead naphthenate, copper naphthenate or other metallic naphthenates and insoluble metallic soaps.

The general object of the invention is to provide new chemical compounds useful as emulsifying, dispersing and wetting agents.

20 A specific object of the invention is to provide new compounds particularly adapted to emulsify water-insoluble soaps of naphthenic acids and other materials ordinarily difficult or impossible 25 to emulsify.

Another object of the invention is to provide new compounds having improved wetting power for use as textile assistants.

Other objects of the invention will in part be 30 obvious and will in part appear hereinafter.

It has now been discovered that when certain 35 esters of naphthenic acids are subjected to sulphonation, products are obtained which possess remarkable emulsifying, dispersing and wetting properties. Hence, the invention comprises, as new compounds and as new emulsifying, dispersing and wetting agents, sulphonation products of esters of naphthenic acids with an unsaturated compound containing 8 or more carbon atoms, 40 selected from the group consisting of fatty alcohols, hydroxy fatty acids and hydroxy fatty esters. The process of the invention comprises esterifying naphthenic acid with an unsaturated compound containing 8 or more carbon atoms, 45 selected from the group consisting of fatty alcohols, hydroxy fatty acids and hydroxy fatty esters and sulphonating the resulting ester.

The invention accordingly comprises the several steps and the relation of one or more of such 50 steps with respect to each of the others, and the product possessing the features, properties and the relation of characteristics, all as exemplified in the detailed disclosure hereinafter set forth and the scope of the invention will be indicated 55 in the claims.

The expression "naphthenic acids" is employed herein to designate the mixture of acids of that name currently obtained in petroleum refining, as well as naphthenic acid or acids which are synthetically prepared or otherwise obtained. It is 5 preferred, however, to use the naphthenic acids derived from the refining of petroleum in view of their relatively low cost.

The first step in the process of producing the products of the invention comprises esterifying 10 naphthenic acids with a hydroxy fatty acid, such as ricinoleic acid, or with a suitable derivative thereof such as castor oil or other esters of ricinoleic acid or hydroxy fatty acids. In lieu of the above hydroxy compounds, mono-hydroxy fatty 15 alcohols containing 8 or more carbon atoms, or substituted derivatives thereof, may be used. It is preferred, however, to esterify the naphthenic acids with hydroxy fatty acids or their hydroxy 20 derivatives.

The esterification may be carried out by direct reaction of the naphthenic acids and the above-mentioned hydroxyl-containing compounds at elevated temperature, with or without the aid of catalysts, or by reaction of potassium or sodium 25 naphthenate with the chloride produced from the hydroxy compounds, or by other known methods.

The sulphonating agents which may be used in the treatment of the above-mentioned esters are 30 well-known to the art and include sulphuric acid, chlorsulphonic acid, oleum, etc. The sulphonation may be carried out on the esters themselves or on solutions of the esters in inert solvents 35 such as chlorinated hydrocarbons, according to any of the well-known sulphonation procedures used in the preparation of sulphated fatty oils.

For a fuller understanding of the nature and objects of the invention, reference should be had to the following examples which are given merely 40 to illustrate some of the products of the invention and method of making the same, and in no way should they be construed in a limiting sense.

Example I

45 100 lbs. of the ester of castor oil and naphthenic acids prepared by heating above 100° C. a mixture of 20 parts by weight of castor oil and 7 parts by weight of naphthenic acids, as outlined in U. S. Patent #2,068,088, is sulphonated for 4 50 hours with 30 lbs. of 66° Bé. sulphuric acid at a temperature of 30° C. The resulting crude sulphonation mass is washed with 250 lbs. of a 5% solution of sodium chloride and neutralized with potassium hydroxide. The sulphonated ester which 55

is obtained after separation of the water has outstanding emulsifying properties for metallic naphthenates and metallic soaps, and may of course be used as an emulsifying agent for other materials, if desired.

Example II

- 100 lbs. of oleyl naphthenate are sulphated for 5 hours with 40 lbs. of 66° Bé. sulphuric acid, 10 at a temperature of about 20° C. The sulphation mass is then washed with 300 lbs. of a 10% solution of sodium chloride and neutralized with sodium hydroxide. After overnight standing, the lower water layer is discarded. The upper layer, 15 consisting of sulphated oleyl naphthenate, is particularly useful as a penetrating, finishing and wetting agent for textile treatments.

Example III

- 20 100 lbs. of the ester obtained by reaction of ricinoleic acid and naphthenic acids at elevated temperatures is sulphated for 4 hours at 30° C. with 30 lbs. of sulphuric acid.

The sulphation mass is washed and neutralized 25 as described in Example I. The sulphated product obtained in this manner has the same uses as the products obtained in Example I or II.

The sulphated esters of the invention possess 30 new and valuable emulsifying and dispersing properties, and they are admirably suited for emulsifying or dispersing materials which are otherwise difficult or impossible to emulsify, such for example, as lead naphthenate, copper naphthenate and other polyvalent metal naphthenates 35 and insoluble metallic soaps.

The above properties make the products of the invention of great value for the preparation of insecticides, wood preservatives, etc. Their remarkable emulsifying properties for the production 40 of the oil-in-water type of emulsions also make them quite suitable as demulsifiers for the water-in-oil type emulsions found in the petroleum fields.

The sulphated esters of the invention are also 45 good wetting agents and possess valuable properties as textile assistants for use in the treatment of various textiles and are also useful in the treatment of leather and other materials where good penetrating action is required.

50 Since certain changes in carrying out the above

process and certain modifications in the product which embody the invention may be made without departing from its scope, it is intended that all matter contained in the above description shall be interpreted as illustrative and not in a limiting sense.

Having described my invention, what I claim as new and desire to secure by Letters Patent is:

1. A sulphation product of an ester of naphthenic acids with an unsaturated compound, containing at least 8 carbon atoms, selected from the group consisting of fatty alcohols, hydroxy fatty acids and hydroxy fatty esters. 10
2. A sulphation product of an ester of naphthenic acids with an unsaturated fatty alcohol containing at least 8 carbon atoms. 15
3. A sulphation product of an ester of naphthenic acids with an unsaturated hydroxy fatty acid containing at least 8 carbon atoms. 20
4. A sulphation product of an ester of naphthenic acids with an unsaturated hydroxy fatty ester containing at least 8 carbon atoms. 25
5. A sulphation product of an ester of naphthenic acids with oleyl alcohol. 30
6. A sulphation product of an ester of naphthenic acids with ricinoleic acid. 35
7. A sulphation product of an ester of naphthenic acids with castor oil.
8. An emulsifying, dispersing and wetting agent comprising essentially a water-soluble salt of a sulphation product of an ester of naphthenic acids with an unsaturated compound, containing at least 8 carbon atoms, selected from the group consisting of fatty alcohols, hydroxy fatty acids and hydroxy fatty esters. 40
9. An emulsifying, dispersing and wetting agent comprising essentially a water-soluble salt of sulphated oleyl naphthenate.

10. An emulsifying, dispersing and wetting agent comprising essentially a water-soluble salt of sulphated ricinoleyl naphthenate. 45
11. An emulsifying, dispersing and wetting agent comprising essentially a water-soluble salt of sulphated naphthenic acids-castor oil ester.
12. An emulsifying, dispersing and wetting agent comprising essentially a water-soluble salt of a sulphation product of an ester of naphthenic acids with an unsaturated fatty alcohol containing at least 8 carbon atoms. 50

ROLAND KAPP. 50
